UNITED STATES PATENT OFFICE.

CHARLES LUKE, OF MILFORD, CONNECTICUT, ASSIGNOR TO THE NEW HAVEN NOVELTY MACHINE COMPANY, OF NEW HAVEN, CONNECTICUT.

DESIGN FOR A PIPE-CO尤LING NUT.

SPECIFICATION forming part of Design No. 33,918, dated January 15, 1901.

Application filed December 19, 1900. Serial No. 40,455. Term of patent 14 years.

To all whom it may concern:

Be it known that I, CHARLES LUKE, a citizen of the United States, residing at Milford, in the county of New Haven and State of Connecticut, have invented and produced a new and original Design for a Pipe-Coupling Nut, of which the following is a specification, reference being had to the accompanying drawings, forming a part thereof.

10 Figure 1 of the drawings shows in side elevation a pipe-coupling nut embodying my design. Fig. 2 is a longitudinal section thereof.

The leading feature of my design for a pipe-coupling nut consists in a cylindrical body 5 presenting a spiral groove externally and internally and a tapered tubular portion extended centrally from the end of said body.

As shown in the drawings, a cylindrical body A has an external spiral groove a' and an internal spiral groove a^2 , and one end of the body, constituting the nut, presents a tapered tubular projection b.

Having fully described my design, what I claim as new, and desire to secure by Letters Patent, is—

The design for a pipe-coupling nut, substantially as herein shown and described.

In testimony whereof I have signed my name to this specification in the presence of two subscribing witnesses.

CHARLES LUKE.

Witnesses:

HENRY G. THOMPSON,
GEORGE E. HAIGHT.
